US00D992728S

(12) **United States Design Patent** (10) Patent No.: **US D992,728 S**
Senff et al. (45) Date of Patent: **** Jul. 18, 2023**

(54) **BASE FOR WATER FLOSSER**

(71) Applicant: **WATER PIK, INC.**, Fort Collins, CO (US)

(72) Inventors: **Oscar C. Senff**, Broomfield, CO (US); **Jeffrey Ladwig**, Seattle, WA (US); **Carson Massie**, Seattle, WA (US); **Adam Weisgerber**, Shoreline, WA (US)

(73) Assignee: **WATER PIK, INC.**, Fort Collins, CO (US)

(**) Term: **15 Years**

(21) Appl. No.: **29/883,446**

(22) Filed: **Jan. 30, 2023**

Related U.S. Application Data

(63) Continuation of application No. 29/839,084, filed on May 18, 2022, now Pat. No. Des. 980,414, which is a continuation of application No. 29/768,954, filed on Feb. 2, 2021, now Pat. No. Des. 956,957, which is a continuation of application No. 29/736,723, filed on Jun. 2, 2020, now Pat. No. Des. 912,241, which is a continuation of application No. 29/681,232, filed on Feb. 22, 2019, now Pat. No. Des. 889,636.

(57) **CLAIM**

We claim the ornamental design for a base for water flosser, as shown and described.

DESCRIPTION

FIG. 1 is a front isometric view of a base for water flosser.

FIG. 2 is a rear isometric view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof; and,

FIG. 8 is a bottom plan view thereof.

The broken lines illustrate portions of the base for water flosser that form no part of the claimed design.

1 Claim, 8 Drawing Sheets
